DISPLAY STAND

Richard J. Johnson, Minneapolis, Minn.

Application May 13, 1948, Serial No. 26,759

2 Claims. (Cl. 211—148)

1

This invention relates to a display stand, and more particularly to an improved structure for securing display shelves, and to the combination with the improved structure of readily interchangeable theme backgrounds for better displaying merchandise.

Among the objects of this invention are the following features and advantages. A display stand is provided which has slots in an upright member arranged in connection with adjustable shelf supports in such manner that various thicknesses of shelves may be used and the shelves may be made of different materials. For example, the shelving may be made of wood, metal or glass of different thicknesses and yet the shelving may be secured firmly by the support to be described below inasmuch as the adjustable supports may be moved to take up the difference in thicknesses of the different shelves. Also, the shelving may be set at an angle to the support without reducing the security of the assembly in a manner to be described below. In addition to the above features, a suitable background may be secured to the upright member which holds the shelves whereby the goods to be displayed may be set off to the best advantage as for example during seasonal displays such as Christmas, Easter, etc.

Other objects and advantages of this invention relate to the details of construction and the arrangement of parts thereof, and will be either pointed out or obvious from the following specifications and claims.

In the drawing, Fig. 1 is a perspective view of the display stand having a Christmas tree background provided thereon,

Fig. 2 is a side elevation view looking from the right toward Fig. 1.

Fig. 3 is a partial detailed front elevation view, and

Fig. 4 is a partial section taken along the line 4—4 of Fig. 3.

Referring more in detail to the drawings, a triangular base 5 is provided to which an upright 6 may be secured at its bottom end. The base 5 may be weighted, or wide enough, or both, to properly support the goods to be displayed thereon. In the drawing, the upright 6 is shown as being substantially vertical, however, it is to be understood that the support may be somewhat at an angle away from vertical, if desired, to lend an alternate artistic effect to the display. Furthermore, the base 5 and the upright 6 may be of different shapes than those shown in the drawing and will in each case be adapted for use

in best displaying the type of goods for which it is intended.

The present display stand by way of illustration, is shown as comprising three shelves 7 secured in transverse slots 8 cut in upright 6. Each slot 8 may extend only approximately half-way into the upright 6, as best shown in Fig. 4. Such structure leaves proper rigidity in the upright 6 and provides a sufficient depth to the slot 8 to receive a shelf 7 and enough engageable surface for the shelf to support it firmly even though it is angled slightly in the slot as in the case of the intermediate shelf 7 shown in Figures 1 and 2.

The shelves 7 may be made of any suitable material such as wood, metal or glass, and of different thicknesses. In the assembly shown in the drawing the shelves are designated as being made of glass. These shelves are designed to support merchandise such as a vase 8 and a figurine 9, for example. As will be readily understood, the different pieces of merchandise displayed may have different weights and hence it is desirable that the shelves 7 be adjustable laterally of the support 6 so that lighter objects may be properly placed outwardly from the upright 6 so as to balance the weight of heavier articles displayed closer to the upright 6. Also, different thicknesses of shelves may be accommodated by adjustable means. As will be made clear below, such adjustments can be conveniently obtained in my invention by use of adjustable supports in combination with the upright 6 and the slots 8 therein.

The shelves 7 are secured in the slots 8 by triangular support brackets 10 which are frictionally engaged with the upright 6 by means of a bolt 11. The bolt 11 passes through a hole 12 in the triangular bracket 10 and passes through an oversize hole 13 in the upright 6. A washer 14 and a wing nut 15 complete the bolt assembly. When the wing nut 15 is loosened, the bracket 10 can be slipped down and the shelf 7 inserted into the slot 8. The shelves 7 may be angled for an artistic effect, as is the intermediate shelf in Figs. 1 and 2, and may be slid laterally more or less, as in the lower shelf 7, Fig. 1, to provide a proper support and sufficient surface for displaying goods. With a shelf 7 in a slot 8, the cooperating bracket 10 may be slid upwardly to firmly engage the lower surface of the shelf, and in that position the wing nut 15 may be tightened again, whereby the friction between the bracket 10 and the upright 6 will retain the assembly in place. Such upward adjustability also will accommodate different thicknesses of shelves,

and beaded or moderately flanged edges. It is to be noted that the shelf can be firmly engaged against the upper surface of the slot 8 when the bracket 10 is pressed snugly against the lower surface of the shelf, and that the engagement is distributed over a substantial area of both the slot 8 and the bracket 10. Due to such large area of engagement, the tendency for shaking loose of a shelf as a result of jarring and bumping is reduced substantially over structures known hitherto.

Referring now again to Figs. 1 and 2, the base 10 has an upwardly extending rear brace 16 which will lend rigidity to the assembly and also provide a surface spaced away from the back of the upright 6. Another block 17 having like thickness, may provide a similarly spaced surface at the upper portion of the upright 6. On these two surfaces, a background sheet 18 may be secured such as by pins or tacks 19, for example. As shown in the drawing, the background sheet 18 is of corrugated material and is cut out in the shape of a Christmas tree. Such a display will lend a seasonal atmosphere to the merchandise displayed during the Christmas season, and the articles held on the shelves 7 will appear as being held on the Christmas tree. It is to be understood that any desirable background can be used to obtain a proper theme, either seasonal or otherwise, for displaying merchandise at different periods of the year. A stiffener strip 20 may be attached to the block 17 at the rear of the background sheet 18 if desired to support that portion of sheet 18 above the upright 6.

While I have explained in detail one particular embodiment of my invention, it is to be clearly understood that other modifications may occur to those skilled in the art. For this reason, I wish not to limit my invention to the specific embodiment shown and described.

What I claim is:

1. A display stand comprising a base, an upright secured at its lower end to said base, said upright having at least one transverse slot therein joining its forward surface, said upright also having below said slot an opening projecting therethrough from front to rear, a shelf of lesser thickness than the distance between the upper and lower horizontal portions of said upright defining said slot, said shelf projecting forwardly from said upright and having a rear edge portion

received within said slot, a bracket located at the forward side of said upright having a top surface extending laterally of said upright below the shelf, a bolt of smaller diameter than said opening passing through said bracket and opening and vertically adjustable relative to said upright and a nut cooperating with said bolt for securing said bracket frictionally into engagement with said upright and shelf after said bracket and bolt have been vertically adjusted on said upright.

2. A display stand comprising a base, an upright secured at its lower end to said base and having at least one substantially horizontal cross slot therein, a shelf of lesser thickness than the distance between the upper and lower horizontal portions of said upright defining said slot, said shelf being received partially within said cross slot, a shelf supporting bracket having one surface adapted to bear against said upright and another surface adapted to bear against the underside of said shelf, and means mounted on said upright and vertically adjustable relative thereto and relative to said shelf for securing said bracket to said upright and for clamping said shelf in said slot.
